QUICK-ACTING CLOSURE FOR TUBES,
BOTTLES, AND THE LIKE

Solomon C. Endicott, Eugene, Oreg.

Application March 30, 1936, Serial No. 71,761

1 Claim. (Cl. 215—70)

My present invention relates to that general class of devices which are employed as closures for receptacles of various types and, more specifically, to a quick-acting closure for tubes, bottles, and the like.

There is an ever increasing demand for a closure to be used on containers for cosmetics, dentifrices and materials of general use, either in the form of liquids, pastes, or powders which, because of the frequent use of the same, requires a closure which will fully seal the contents, prevent spilling and which can be opened easily with full assurance that the closing device will not become lost. It is to supply a device to meet these recognized needs that I have created my quick-acting closure.

My present invention follows to a degree the general design of my receptacle closure shown in my United States Letters Patent Number 1,715,452. In my present construction, however, I have overcome certain deficiencies of my former closure. I have provided means that will assure its more satisfactory operation; means which will assure against any possible losing of the closure device and which because of its present construction will lend itself more readily to a wider field of use in that it can be very economically manufactured in quantity.

Other and more specific objects will be apparent from the following description taken in connection with the accompanying drawings, wherein—

Figure 1 is an elevation of my closure of a type that might be used quite generally as a closure for bottles, collapsible tubes, or any other similar use.

Figure 2 is a vertical, sectional view through the device of Figure 1, showing the same in its closed position.

Figure 3 is a sectional view similar to Figure 2 showing the first stage of the opening of my closure.

Figure 4 shows my device entirely open, making available the material stored in the receptacle and further showing the operation of the friction securing means which prevents the further movement of the thread engaging means.

Figure 5 is an elevation, partly in section, with the cutting plane revolved ninety degrees from Figure 4.

Figure 6 illustrates a modified form of construction in which a single thread is used on the receptacle.

Figure 7 illustrates my closure as applied to an air valve stem of the type used on automobile tires.

Figure 8 shows in an exploded perspective view the essential parts making up my present device.

Figure 9 illustrates my device as applied to a

collapsible tube such as used for toothpaste, shaving cream, cosmetic preparations and the like.

Figure 10 is a perspective view showing the convenient manner in which my closure may be used as on a powder can, or bottle containing liquid, illustrating how the material can be shaken, or poured, from the container without in any way having the closure device interfere with the operation.

Figure 11 is a cross-sectional view through the collar used with my device illustrating more completely the difference in depth of the securing grooves which accomplish a very definite purpose in my present design.

Referring to the drawings, throughout which like reference characters indicate like parts, 14 designates the usual reduced, neck portion as is common with many types of containers such as collapsible tubes, bottles and the like. Into this neck I provide, preferably, two oppositely disposed threads, or grooves, as 16 and 17. These threads as distinguished from those formerly used as disclosed in my Patent 1,715,452 do not extend to the end of the neck portion but stop somewhat short of the end after the showing, particularly of Figures 5 and 8. These threads are molded, or otherwise formed, as grooves having, preferably, uniform depth throughout.

Disposed between the ends of the threads or grooves thus provided and the extreme end of neck portion are cam guideways 19 and 20. These have at the face of neck 14, substantially the same depth as threads 16 and 17, but as they approach the end of the threads they taper toward the periphery of the neck and entirely run out before they meet the end of the thread. These are to provide means for assembling my closure which will be more fully explained later.

Encircling neck 14 and of a size to provide reasonable clearance therefrom, is the closure collar 22. This is provided with a straight, cylindrical bore, thereby being distinguished from my former construction which was threaded on its inner surface. The outer surface of collar 22 may take any desired shape. It has, however, been found most desirable to provide it with two opposite, parallel sides as 24 and 25. These sides are pierced with openings 26 and 27 whose axes are coaxially aligned. Disposed in a plane normal to the longitudinal axis are securing grooves 29 and 30. These are to accommodate bail member 32.

In the same vertical plane of openings 26 and 27 and parallel to the longitudinal axis of collar 22, I provide additional grooves 34 and 35. These grooves run from openings 26 and 27, upwardly to the upper surface 36 of collar 22, and as in the case of grooves 29 and 30, they also are made to accommodate bail member 32. One feature that greatly influences the operation of my closure is the fact that grooves 34 and 35 are

of less depth than grooves 29 and 30. The relationship being substantially as shown in Figure 11.

Adapted for co-action with collar 22 is the cap, 5 or closure member proper, 40. This, as is true also in the case of collar 22, may be formed from any suitable materials such as die casting the same of metal, or by molding them from the resin base materials such as Bakelite. Inside of 10 cap 40 I provide a sealing gasket 42. This may be cork, rubber, or other suitable, compressible materials. Secured to cap 40 is bail member 32. The exact manner of securing the two together will be largely indicated by the conditions under 15 which the device is to be used. It is desirable, particularly for closures wherein neck 14 is small, to have bail 32 so secured to cap 40 that the entire cap, and bail, as a unit will pivot about the inturned ends of bail 32 as 44 and 45. It will be understood it is believed that if large closures 20 are to be accommodated it might be desirable to have caps 40 pivot upon the straight bar 47 of bail 32 to the end that collar 22 would not have to be moved so far up the neck in order to make it 25 possible to swing the cap free of the same.

In Figure 6 I have indicated a modified form of my present device in which all the described characteristics of cap 40 are retained but collar 52 departs to a degree from the form of collar 30 22 in that while openings 54 and 55 are co-axially disposed they are not in a plane normal to the axis of neck 14. This arrangement might be desirable under certain conditions where it is considered necessary to use a single thread 56 as distinguished from the other form in which two 35 threads or grooves are used.

In Figure 7 I have illustrated my closure means 40 as applied to a tire valve stem 60. The construction of the various parts is exactly as described above and it functions in the identical manner. 45 It does, however, provide a very convenient means of closing such a device in a secure manner with the various parts so securely tied together that there would never be any danger of loss. The cap itself would be well out of the range of the air hose attachment if the side legs of bail 32 are made substantially after the showing of Figure 7, somewhat longer than illustrated in the other views. This necessitates somewhat longer grooves at 61, which grooves, however, would 50 have the same function and otherwise be similar to grooves 19 and 20.

Method of operation

Assuming that the various parts of my device 55 have been constructed along the lines indicated, the first operation in the use of the cap will be to assemble the closure as a unit. To do this the first operation will be to engage the inturned ends 44 and 45 in openings 26 and 27 of collar 22.

The next operation will be to slide collar 22 over neck portion 14 and to engage the inturned ends 44 and 45 of bail 32 in guideways 19 and 20. A continued downward pressure will now spring 60 outwardly these inturned ends until they pass far enough down to engage the upper limit of grooves 16 and 17. The ends will now spring inwardly to their normal position as indicated in Figures 2 and 3. In this connection it should be 65 pointed out that the arms carrying the inwardly extending detents as 44 and 45, should be of re-

silient material. They need not necessarily be formed of a single piece as indicated in the drawings, but it has been found that piano wire fashioned after the forms indicated, is a very satisfactory means.

The closure is now in condition for use with 5 detents 44 and 45 providing the thread or groove engaging means and in this respect taking the place of the threads formerly employed in the structure shown in my Patent Number 1,715,452. 10

As observed in Figures 2, 3 and 6 it will be noticed that the ends of detents 44 and 45 do not engage the bottom of grooves 16 and 17, or the bottom of groove 56. Consequently, as long as the cap is positioned by grooves 34 and 35 after 15 the showing of Figure 3, the whole device can be screwed very easily, either upwardly, to release the cap, or downwardly to effect a secure seating. For normal use the pitch of thread 16 and 17 should be sufficient so that a half turn of the cap 20 will release it from neck 14 so that it may be swung over into the position indicated in the Figures 4, 5, 7 and 10, this position being assured by having detents 44 and 45 abut a shoulder at the upper ends of the threads. When in this position 25 as illustrated specifically in Figure 4, the ends of detents 44 and 45 are in secure engagement with the bottom of the thread and, as illustrated by the dotted line showing at 58 and 59, there is sufficient clearance between the bottom 30 of grooves 29 and 30 and the legs of bail member 32 so that the full force of the inward pressure, that can be exerted by bail 32, can be applied to the bottom of grooves 16 and 17, and thus lock the device in its position of use. In this position 35 the container can be shaken as indicated in Figure 10 or if the container is a tube as indicated in Figure 9 it may be laid down and still the cap will not creep upon the thread so that when it is swung back into axial alignment there will 40 be no interference between the cap and neck 14, and a half turn in the reverse direction will be sufficient to seat the cap upon gasket 42 and securely seal the container. It is desirable to point out that there may be certain conditions of use 45 where the steep pitch of threads 16 and 17 might cause the closure to loosen under vibration or unusual strain. This can be overcome by decreasing the pitch with sufficient lengthening of threads 16 and 17 so that one or more full turns 50 will be required to operate the closure.

The foregoing description and the accompanying drawings are believed to clearly disclose a preferred embodiment of my invention but it will be understood that this disclosure is merely illustrative and that such changes in the invention 55 may be made as are fairly within the scope and spirit of the following claim.

I claim:

In a closure the combination with a receptacle 60 including a neck having exterior spiral grooves thereon and a pair of opposed diverging grooves on said neck, of an annular collar for said neck having opposed openings therethrough, horizontal, tangentially disposed grooves on its outer 65 face, and vertically disposed grooves terminating in said tangentially disposed grooves; a resilient bail having a pivotally mounted cap thereon, and the ends of said bail terminating in inturned pins adapted to journal in said openings.

SOLOMON C. ENDICOTT.
